United States Patent Office.

CHARLES H. WATERS, OF GROTON, MASSACHUSETTS.

Design No. 3,789, dated December 14, 1869.

DESIGN FOR A FLOWER-STAND.

The Schedule referred to in these Letters Patent and making part of the same.

I, CHARLES H. WATERS, of Groton, in the county of Middlesex, and State of Massachusetts, have invented and produced a new and original Design for a Revolving Flower-Stand, of which the following is a specification.

The nature of my design is fully represented in the accompanying photographic illustration, to which reference is made, the upper part *a* being pivoted upon the standard *b*.

Claim.

I claim, as my invention, the design for a revolving flower-stand, as described and shown.
